UNITED STATES PATENT OFFICE.

VICTOR M. WITMER, OF MILWAUKEE, WISCONSIN.

MACHINE FOR BENDING BARS.

Application filed January 10, 1927. Serial No. 160,226.

This invention relates to improvements in machines for bending bars.

It is the primary object of the present invention to provide a machine for forming angular bends in bars.

A further object of the invention is to provide a machine of the class described which may be either manually or motor operated.

A further object of the invention is to provide a machine of the class described in which the angularity of the bends imparted to the bars may be regulated.

A further object of the invention is to provide a machine of the class described which may be operated to put any desired number of bends in a bar of any length.

A further object of the invention is to provide a machine of the class described which will accommodate bars of varying thicknesses.

A further object of the invention is to provide a machine for bending bars which is of very simple construction, is strong and durable, is easily operated, and is well adapted for the purpose described.

With the above and other objects in view the invention consists of the improved machine for bending bars, and its parts and combinations as set forth in the claims, and all equivalents thereof.

In the accompanying drawings in which the same reference characters indicate the same parts in all of the views:

Fig. 1 is a plan view of the improved machine for bending bars with the parts in normal position and a bar in place to be operated on;

Fig. 2 is a plan view showing the position of the parts after bends have been imparted to the bar;

Fig. 3 is a sectional view taken on line 3—3 of Fig. 1;

Fig. 4 is another sectional view taken on line 4—4 of Fig. 1;

Fig. 5 is a detail view showing a bar bent by the machine, and on a smaller scale; and

Fig. 6 is a similar detail view showing another character of bends which may be given to a bar.

Referring now more particularly to the drawings it will appear that the numeral 8 indicates the flat base of the machine which is adapted to be stationed upon a suitable table or support. The base 8 is formed with three aligned bearing portions 9, 10, and 11

in which are journaled upstanding stud shafts 12, 13, and 14 respectively. Each of the shafts 12 and 14 carries a large gear 15 and 16 respectively, both of the same diameter, while the intermediate shaft 13 carries a smaller intermediate gear 17 in mesh with both of the gears 15 and 16.

A right angular lever 18 is mounted at its intermediate point on the upwardly extending reduced portion 12' of the shaft 12 and said lever is also pinned to the gear 15 so that the two will operate together. A straight lever 19 is mounted at one end portion on the shaft 14 and said lever is pinned to the gear 16 to operate therewith. The outer end portion of said lever 19 is pivotally connected with one end portion of a third lever 20 which is pivotally connected at its other end portion with the adjacent end portion of the right angular lever 18 by means of a pin 26. It will be noted that the end portions of the levers 18 and 19 are formed with a plurality of apertures 21 and 22 by which means the pivotal connections for the lever 20 may be adjusted with respect to the ends of the levers 18 and 19 for a purpose hereinafter to be explained.

The lever 20 is formed with an upstanding portion 23 forming a guide and support and against the vertical face 24 of which a bar 25 is placed. The bar, inwardly from the portion in engagement with the face 24 is engaged between the pivot pin 26 and a roller 27.

The lever 18 is formed with an upstanding portion 28 against the face of which a portion of the bar 25 rests and the bar is also engaged between the reduced shaft portion 12' and a roller or pin 29 mounted on a block 30 adjustably held on the face of the lever 18, providing means for the accommodation of bars of different thicknesses.

A platform member 31 is built up on the lower left hand corner of the base member 8, in Fig. 1 and the plane of the same is on a level with the supporting surfaces of the members 18 and 20. Said platform is adapted to support the inner end portion of the bar to be bent. A pivotal cam member 32 is positioned at the inner portion of the platform to bear against the bar 25 and to prevent it from bowing when bent. Apertures 33 are also formed in the platform for the reception of a guide or gauge pin 34.

Fig. 1 illustrates the parts of the machine in normal position and the bar 25 is placed

as shown. Bars of different diameters or thicknesses may be accommodated by adjusting the block 30 and substituting for the pins 26 and 34, pins of a larger or smaller diameter, as the case may be. To operate the machine, power may be applied to any of the gears or levers, either manually or by motor, to move the large gears and levers in a clockwise direction as shown in Fig. 2. This will 5 result in the bar being bent in two places, with each movement of levers as shown, and the angularity and extent of the bends is controlled by the distance the levers are turned. If the bar is of such a length that 10 more bends are required it is removed and the remaining straight portion re-positioned for successive operations. The spaced apertures 21 and 22 permit the insertion of the pivot pins for the lever 20 in any corresponding pair of apertures to vary the disposition 15 of the lever 20 with respect to the end portions of the levers 18 and 19. This adjustment, together with the positioning of the gauge pin 34 in a selected aperture 33, varies 20 the character of the bends imparted to the bar 25 by the machine. Fig. 6 illustrates a bar 25' bent when the parts have been adjusted in a manner as described, while Fig. 5 illustrates a bar 25' bent with the machine adjusted as 25 shown.

From the foregoing description it will be seen that the improved machine for bending bars is of very simple and novel construction, and is well adapted for the purposes set forth.

35 What I claim as my invention is:

1. A machine for bending bars, comprising a base, a pair of connected gears revolvably mounted on the base, a lever secured to each of said gears, an intermediate lever pivotally connected with each of said first mentioned levers, the intermediate lever and one of the other levers being formed with guide means to receive a bar, and means on said levers to engage a bar at intermediate points to bend said bar at said engaged points when said levers are moved from normal position.
2. A machine for bending bars, comprising a base, a pair of connected gears revolvably mounted on the base, a lever secured to each of said gears, an intermediate lever pivotally connected with each of said first men-

tioned levers, the intermediate lever and one of the other levers being formed with guide means to receive a bar, a brace for an outer portion of a bar on the intermediate lever, 55 a brace for an opposite outer portion of a bar on the base, and means on said levers for bendingly engaging intermediate portions of a bar, the relative positions of said means being changed when the levers are moved. 60

3. A machine for bending bars, comprising a base, a pair of connected gears revolvably mounted on the base, a lever secured to each of the gears, an intermediate lever adjustably pivotally connected with each of said first mentioned levers, the intermediate lever and one of the other levers being formed with adjustable guide means to receive a bar, a brace for an outer portion of a bar on the intermediate lever, a brace for an opposite 70 outer portion of a bar on the base, and means for operating the levers to change the relative positions of said guide means whereby bends are formed in a bar. 75

4. A machine for bending bars, comprising a base, a pair of gears revolvably mounted thereon, an intermediate gear in mesh with each of the first mentioned gears, a bending lever carried by one of said first mentioned gears, a lever carried by the other of said gears, an intermediate lever pivotally connected with each of said other levers, and bar engaging means on the base, the bending lever, and the intermediate lever. 80

5. A machine for bending bars, comprising a base, a pair of gears revolvably mounted thereon, an intermediate gear in mesh with each of the first mentioned gears, a bending lever secured to one of the first mentioned gears, a lever secured to the other of said gears, an intermediate lever adjustably pivotally connected with each of said other levers, the intermediate lever and the bending lever being provided with adjustable bar means on said base, all of said bar engaging 95 means normally being in alinement, and means for simultaneously moving said levers whereby the bar engaging means are angularly disposed with respect to each other to bend a bar engaged thereby. 100

In testimony whereof, I affix my signature.

VICTOR M. WITMER.
